UNITED STATES PATENT OFFICE.

LOUIE S. HART AND NORMAN E. LEE, OF NEW HAVEN, WEST VIRGINIA.

EMERGENCY FUEL-TANK FOR MOTOR-VEHICLES.

1,126,995.

Specification of Letters Patent.

Patented Feb. 2, 1915.

Application filed September 19, 1914. Serial No. 862,599.

To all whom it may concern:

Be it known that we, LOUIE S. HART and NORMAN E. LEE, citizens of the United States, residing at New Haven, in the county of Mason and State of West Virginia, have invented certain new and useful Improvements in Emergency Fuel-Tanks for Motor-Vehicles, of which the following is a specification, reference being had to the accompanying drawings.

10 This invention relates to motor vehicles and particularly to an emergency fuel tank and feeding device.

An object of this invention is the provision of an emergency fuel tank in which a supply of fuel is normally contained therein to be used in the carbureter only when the amount of gasoline in the main tank is so small that the same will not flow to the carbureter when the vehicle is climbing a hill, the emergency tank being so arranged that the fuel contained therein will automatically flow to the carbureter upon the opening of a valve which normally prevents the fuel from reaching the carbureter.

15 A further object of this invention is the provision of an emergency fuel tank which is connected to one arm of a three-way valve casing, the main fuel tank being connected 20 to another arm of the casing, and the remaining arm being connected to the carbureter of the motor so that when the valve is disposed to provide communication between the main tank and the carbureter, communication 25 between the emergency tank and the carbureter is cut off, and vice versa.

With these and other objects in view, our 30 invention consists in the novel construction, combination and arrangement of parts to be hereinafter more fully described, claimed and illustrated in the accompanying drawing, in which—

Figure 1 is a side elevational view of our 35 device; Fig. 2 is a top plan view thereof; Fig. 3 is a front view; Fig. 4 is a longitudinal sectional view of the valve and casing used in connection with the device; Fig. 5 is a top plan view of the valve casing showing the valve in section; and Fig. 6 is a top 40 plan view, showing the manner of connecting the valve operating frame to the operating lever.

Referring more particularly to the drawing, the numeral 1 designates the frame of 45 a motor vehicle which is provided with the front wheel fenders 2, and secured to the

under face of the left hand fender is an emergency fuel tank 3 which is provided with a filling neck 4 projecting upwardly through the fender.

5 The numeral 5 designates the carbureter of the motor, in which one tubular arm 6 of a three-way valve casing 7 is connected, the remaining tubular arms of the casing being arranged in alinement with each other 65 in a plane at right angles to the arm 6.

Extending from the bottom of the tank 3 is an outlet pipe 8 which is connected in the forwardly extending tubular arm 9 of the valve casing 7, and extending rearwardly from the rear arm 10 of the valve casing is a feed pipe 11 which extends from the valve casing to the main fuel tank 12 of the motor.

70 Formed in the valve casing 7 at the junction of the tubular arms is a vertical opening in which a rotary valve 13 is mounted, the valve having a pair of openings 14 and 15 formed therein which extend at right angles to each other and communicate at 75 their inner ends. Extending laterally from the valve 13 is a pin 16 which rests in an arcuate groove 17 in the upper face of the casing 7, whereby to limit the rotation of the valve in either direction so that when 80 the opening 15 in the valve registers with the tubular arm 10 the opening 14 registers with the arm 6, and when the opening 15 registers with the arm 6 the opening 14 registers with the arm 9. By this arrangement 85 it will be seen that when fuel is permitted to flow from the main tank to the carbureter, the flow of fuel from the emergency tank to the carbureter is cut off, and when the valve is turned to permit the flow 90 of fuel from the emergency tank the fuel supply from the main tank is cut off. Extending inwardly from the valve is an arm 95 100 105 110

115 through the medium of which the valve is operated, and connected to the free end of the arm 18 is the forward end of a connecting rod 19 which extends rearwardly of the vehicle and is connected at its rear end to one end of a crank shaft 20 which extends across the vehicle under the floor thereof. Connected to the other end of the crank shaft 20 is a lever 21 which extends upwardly through a slot in the floor of the vehicle, the upper end of the lever being engaged against a spring bar 22 which is provided with a plurality of spaced notches 23 formed therein, the lever being

adapted to engage in any one of the notches to hold the valve 13 in such position so that either the main tank 12 communicates with the carbureter, or the emergency tank 3 communicates therewith. A sheet of asbestos or other non-heating material 24 is arranged between the upper face of the emergency tank 3 and the fender to protect the tank from the heat of the sun's rays 10 and the heat of the motor, the asbestos sheet also preventing the tank from rattling against the fender.

In the practical use of our device, the vehicle is operated in the ordinary manner 15 with the tank 12 containing the main store of fuel, the tank 12 being in communication with the carbureter 5 by arranging the hand lever 21 in the notch of the spring bar 22 which will hold the valve 13 with the opening 15 registering with the tubular arm 10 which is connected with the feed pipe of the main tank 12; and the opening 14 registering with the arm 6 which communicates with the carbureter. Should the vehicle be 25 climbing a steep incline with the supply of fuel in the main tank so low that the fuel will not flow to the carbureter, the lever 21 may be immediately actuated to rotate the valve 13 so that the opening 14 therein will 30 communicate with the arm 9, to which the feed pipe 8 of the emergency tank is connected, so that the opening 15 will communicate through the arm 6 with the carbureter, whereupon the supply of fuel contained 35 within the emergency tank will immediately flow into the carbureter so that the machine will not be stalled on a hill. When the valve 13 is in such position that the fuel is allowed to flow from the emergency tank to the carbureter, communication between the valve 40 casing and the main tank is cut off so that the fuel from the emergency tank will be prevented from flowing back into the feed pipe of the main tank.

Having thus fully described our invention, what we desire to claim and secure by Letters Patent is:

1. In combination with a motor vehicle having a carbureter, a valve casing having 50 a tubular arm connected with said carbureter, said casing having tubular arms extending therefrom in a direction at right angles to the first mentioned arm, a main fuel tank, a feed pipe extending from said 55 main tank and connected with one of the other arms of said valve casing, an emergency tank, a feed pipe extending from the

emergency tank to the remaining arm of the valve casing, a rotary valve mounted in said casing, said valve having a pair of openings 60 therein extending at right angles to each other and communicating at their inner ends, and means for rotating said valve whereby to open communication between one of said tanks and said carbureter while 65 communication between the other of said tanks and said carbureter is shut off.

2. In combination with a motor vehicle having a carbureter, a main fuel tank arranged rearwardly of the carbureter, a feed 70 pipe extending from the main pipe to the carbureter, an emergency tank connected to one of the front fenders of the vehicle forwardly of the carbureter, and means for preventing the flow of fuel from the emergency 75 tank to the carbureter when the main tank is in communication with said carbureter, and vice versa.

3. In combination with a motor vehicle having a carbureter, a valve casing connected to the carbureter, a main fuel tank, a feed pipe extending from said main pipe and connected to the valve casing, an emergency tank, a feed pipe extending from the emergency tank and connected to the valve 85 casing, a valve mounted in the casing, and means for operating the valve whereby to open communication between one of the tanks and the carbureter while communication 90 between the other of the tanks and the carbureter is shut off.

4. In combination with a motor vehicle having a carbureter, a main fuel tank and an emergency tank, a valve casing having a plurality of tubular arms, one connected with 95 the main fuel tank and one connected with the emergency tank, and one connected with the carbureter, a valve mounted in said casing and adapted to establish communication between either one of the arms leading to 100 the tanks and the carbureter, and means for shifting the valve whereby to open communication between one of said tanks and said carbureter, and simultaneously close communication between the other of said tanks and the carbureter.

In testimony whereof we hereunto affix our signatures in the presence of two witnesses.

LOUIE S. HART.
